UNITED STATES PATENT OFFICE.

WILLIAM WAHRT, OF BROOKLYN, NEW YORK.

MASSAGE APPARATUS.

Application filed April 1, 1925. Serial No. 19,922.

This invention relates to improvements in massage devices.

The primary object of the invention resides in a massage device for the skin which 5 may be passed thereover by the person desiring the massage and which is especially adapted for use as a head massage for agitating the scalp to excite the tissues which become clogged thereby tending to improve 10 the growth of hair. However, the same may be used upon the face for removing wrinkles and other blemishes therefrom.

Another object is to provide a massage apparatus having a spindle which is adapted 15 to interchangeably receive massaging members of different forms depending upon the size and shape of the massage surface desired, and over which members, a flexible cover may be inserted for receiving a substance which in turn is imparted to the parts 20 to be massaged.

A further object resides in a massage apparatus which is simple in construction, 25 cheap of manufacture and easy to disassemble for cleaning purposes and for interchangeably receiving massage members of various shapes.

With these and other objects in view, the 30 invention resides in certain novel construction and combination and arrangement of parts, the essential features of which are hereinafter fully described, are particularly pointed out in the appended claims, and are illustrated in the accompanying drawing, 35 in which:—

Figure 1 is a perspective view of my improved massage device with the massaging members removed.

Figure 2 is a vertical longitudinal sectional view showing the massaging members in position.

Figure 3 is a transverse sectional view on the line 3—3 of Figure 2.

Figure 4 is a detail sectional view showing the manner of mounting a single massage member upon the spindle.

Figure 5 is a detail sectional view of a modified form of a massage member.

Figure 6 is a detail perspective view of the medicated cover.

Referring more particularly to the drawing, the reference numeral 10 designates my improved massage device which includes a frame 11 formed of a pair of sections 12 and 13. The sections 12 and 13 are formed 55 of relatively heavy wire, the section 12 be-

ing bent to provide a relatively horizontally disposed spindle 14 at one end and an upwardly extending arm 15 at its other end and to which a manipulating handle 16 is 60 attached. The section 13 is similar to the section 12 but one end of the same is provided with an eye 17 while the other end is adapted to lie parallel to the arm 15 and is provided with an eye 18 for receiving a bolt 65 19 which passes through the arm 15 and which sections are removably secured together by a thumb nut 20 which co-acts with the free end of the bolt.

A plurality of interchangeable rollers 21 70 are carried by the spindle 14 and are held thereon by a thumb nut 22 which co-acts with the threaded end of the spindle which projects through the eye 17. These rollers may be formed of a solid material such as 75 wood or rubber, and if desired the same may be a hollow cylinder to reduce the weight of the device. A stop 23 is formed on the spindle and the nut 22 co-acts with the same to jam the rollers into tight engagement to provide a continuous massage surface.

The rollers 21 are provided with radially extending fingers 24. In the preferred form, 80 the fingers are formed of a yieldable material such as rubber, and if desired, the same may be of various lengths to provide a curved massaging surface to fit the contour of the parts to be massaged.

In applying the massaging members to 85 the spindle, the thumb nut 22 is removed from the spindle and the nut 20 loosened to permit the section 13 to swing about the bolt 19 out of the path of movement of the massage members when the same are 90 passed over the free end of the spindle. When the rollers have been applied, the arm is moved to its former position and the thumb nuts tightened.

Should it be desired to have a relatively 100 small massage surface, the rollers may be removed with the exception of the one or ones desired to make up the massage surface, after which a spacing sleeve 25 is inserted 105 on the spindle between the stop 23 and the end roller as shown in Figure 4. The sleeves may be of various lengths to provide for the interchangeable relation of the various rollers.

In Figure 5, I have shown a slightly modified form of the massage member indicated by the numeral 26 and which is formed of a 110

sleeve 27 from which extend posts 28 having their free ends formed with heads 29. Cylinders 30 are slidable over the posts and limited in their outward movement by the heads 29. Interposed between the end of each cylinder and the respective posts is a spring 31 which is adapted to normally hold the cylinders in extended position but which are yieldable for movement when pressure is applied to the roller when in use.

In Figures 2 and 6, I have shown a flexible cover 32 which is adapted to be passed over the massaging rollers when assembled on the spindle, and which is adapted to apply medicinal substances to the parts to be massaged simultaneously with the massage action set up by the fingers.

When in use, the user grasps the handle 16 and moves the device back and forth under pressure over the surface to be massaged to agitate the skin in order to excite the tissues for increasing circulation of the blood. It will be noted that various shapes of massaging members may be applied depending upon the size and shape of the massage surface desired.

While I have described what I deem to be the most desirable embodiment of my invention, it is obvious that many of the details may be varied without in any way departing from the spirit of my invention, and I therefore do not limit myself to the exact details

of construction herein set forth nor to anything less than the whole of my invention limited only by the appended claims.

35

What is claimed as new is:—

1. A massage apparatus comprising a frame formed of a pair of pivotally connected sections, a spindle on one of said sections, rollers carried by said spindle adapted to swing in the same plane, the free end of said other section engaging the end of said spindle, and a retaining nut removable from the free end of said spindle for holding the rollers thereon.

45

2. A massage apparatus comprising a frame constituting a pair of pivotally connected sections adapted to swing on the same plane, a spindle on one of said sections having its free end screw threaded, an abutment at one end of said spindle, a massage member rotatably mounted on said spindle, a sleeve encircling said spindle and interposed between said massage member and said abutment, an eye on the free end of the other of said sections for the passage of the threaded end of said spindle, and a clamping nut co-acting with the threaded end of said spindle for retaining said massage member and sleeve thereon.

50

In testimony whereof I have affixed my signature.

55

WILLIAM WAHRT.
